CLAIM

The ornamental design for a heat transfer core body, as shown and described.

DESCRIPTION

FIG. 1 is a top perspective view of a heat transfer core body; FIG. 2 is a bottom perspective view of the heat transfer core body shown in FIG. 1;

FIG. 3 is an elevation view showing a first perimeter portion of the heat transfer core body shown in FIG. 1;

FIG. 4 is an elevation view showing a second perimeter portion of the heat transfer core body shown in FIG. 1;

FIG. 5 is an elevation view showing a third perimeter portion of the heat transfer core body shown in FIG. 1;

FIG. 6 is an elevation view showing a fourth perimeter portion of the heat transfer core body shown in FIG. 1;

FIG. 7 is a top plan view of the heat transfer core body shown in FIG. 1;

FIG. 8 is a bottom plan view of heat transfer the core body shown in FIG. 1;

FIG. 9 is another perspective view of the heat transfer core body shown in FIG. 1;

FIG. 10 is an elevation cross-sectional view of the heat transfer core body shown in FIG. 1 taken along line 10-10 in FIG. 9;

FIG. 11 is an elevation cross-sectional view of the heat transfer core body shown in FIG. 1 taken along line 11-11 in FIG. 9;

FIG. 12 is an elevation cross-sectional view of the heat transfer core body shown in FIG. 1 taken along line 12-12 in FIG. 9;

FIG. 13 is a top perspective cross-sectional view of the heat transfer core body shown in FIG. 1 taken along line 13-13 in FIG. 9;

FIG. 14 is a top perspective cross-sectional view of the heat transfer core body shown in FIG. 1 taken along line 14-14 in FIG. 9;

(Continued)

FIG. 15 is a top perspective cross-sectional view of the heat transfer core body shown in FIG. 1 taken along line 15-15 in FIG. 9; FIG. 16 is a top plan cross-sectional view of the heat transfer core body shown in FIG. 1 taken along line 16-16 in FIG. 9; FIG. 17 is a top plan cross-sectional view of the heat transfer core body shown in FIG. 1 taken along line 17-17 in FIG. 9; FIG. 18 is a top plan cross-sectional view of the heat transfer core body shown in FIG. 1 taken along line 18-18 in FIG. 9; and, FIG. 19 is a top plan cross-sectional view of the heat transfer core body shown in FIG. 1 taken along line 19-19 in FIG. 9. The broken lines illustrate portions of the heat transfer core body that form no part of the claimed design. For example, the broken lines along the boundaries of the heat transfer core body indicate that the heat transfer core body of the claimed design may have a greater number of repeating unit cells than illustrated. The cross-hatching lines indicate planes of the heat transfer core body that intersect a sectioning plane. The cross-hatching lines form no part of the claimed design.
